ROOFING CONSTRUCTION

John P. Willock and John A. McEwen,
Pittsburgh, Pa.

Application November 15, 1932, Serial No. 642,789

1 Claim. (CL 108--9)

This invention relates to building construction, and its general object is to provide a covering designed for a roof and outer walls of a building that can be easily and quickly applied, thoroughly insulates the building against heat and cold, is neat in appearance, fire proof, and is not effected by weather elements including winds of high velocity with the result it will last for a prolong period of time without attention or repairs.

A principal object of the invention is to provide a covering of the character set forth, that includes rigid composition shingles and non-rusting or rust resisting metallic cleats to provide a leak proof connection between confronting portions of the shingles or siding and as a small overlap is all that is necessary, when the cleats are used with the shingles, a large area can be amply and completely covered with a minimum amount of shingles.

Another object of the invention is to provide a shingle cleat that cooperates with securing means for the shingles to hold the latter in cooperative relation with respect to each other and in alignment, and is completely hidden from view by the shingles.

A still further object of the invention is to provide a shingle cleat that is simple in construction, inexpensive to manufacture, easy to apply and extremely efficient in operation and service.

This invention also consists in certain other features of construction and in the combination and arrangement of the several parts, to be hereinafter fully described, illustrated in the accompanying drawing and specifically pointed out in the appended claim.

In describing our invention in detail, reference will be had to the accompanying drawing wherein like characters denote like or corresponding parts throughout the several views, and in which:

Figure 1 is a longitudinal sectional view taken through a roof constructed in accordance with our invention.

Figure 2 is a front view showing the covering applied to a side wall of a building.

Figure 3 is a sectional view taken approximately on line 3--3 of Figure 2.

Figure 4 is a perspective view of our shingle cleat.

Referring to the drawing in detail, the letter A indicates a portion of a roof of a building, and to which our covering is secured, as shown in Figure 1. However, the covering can be ap-

plied to the outer walls of a building as indicated in Figure 2 and the covering includes a sheet 1 of insulating material of the fabric type such as celotex or the like which provides the inner layer for the cover.

The shingles which are indicated by the reference numeral 2 may be of any size and thickness for the purpose intended and are formed from a composition of cement and asbestos or other like material, with the result they are not only fire proof and cannot curl or buckle, but are provided with openings 3 adjacent one of the edges thereof for the purpose of accommodating securing means such as nails or the like 4.

The shingles are arranged in overlapping relation with respect to each other as best shown in Figure 1, and nailed on top of the sheet of insulating material 1 with the result the latter acts as a cushioning means therefor.

The shingles or siding are arranged in end to end relation and in order to provide a leak proof connection between the ends we use a cleat of the type as best shown in Figure 4, that is formed from a single sheet of non-rusting or rust resisting metal such as copper or aluminum, and the cleat includes a body 5 that is elongated and of a width coextensive with the width of the shingles as will be noted upon inspection of Figure 2.

Formed with one end of the body 5 is a right angle flange 6 which acts in the capacity as a hook means and includes a portion disposed in parallelism with the body to engage the top or outer side of the shingles, while the remaining portion of the flange 6 engages the upper edges, with the result the right angle flange holds the shingles in alignment with respect to each other and has a tendency to cooperate with the nails 4 in fixedly associating the shingles. Formed with the body at the longitudinal edges thereof are channel grooves 7 which as shown in Figure 3 are disposed upon opposite sides of the meeting ends of the shingles. These channels are for the purpose of directing water that may seep through the joint between the ends of the shingles, to the outer side of the roof, therefore the cleat not only provides a leak proof connection between the ends of the shingles but also allows for the use of a minimum amount of shingles to cover a relatively large area of space in that the shingles can be overlapped a slight distance as will be apparent upon inspection of Figure 2.

Disposed between the overlapped portions of the shingles are flexible elements 8 in the form

of rope and which is saturated with asphalt and may be formed from hemp or the like, but in any event the flexible elements prevent driving rain from passing between the overlapped portions, as well as act as cushioning means for the shingles as will be apparent.

In applying our covering, the sheets of insulating material are first laid, and the first row of shingles are nailed in place, with a flexible element below the same and arranged adjacent the lower edge of the row. The cleats are then inserted with their body portions underlying the confronting ends of the shingles, and the next row of shingles are nailed in place with the flexible element between the overlapped portions of the first and second rows. This operation is continued until the entire roof or side wall is completely covered, and it will be obvious that a roof or side wall that is finished with our covering will last for an indefinite period of time without attention or repairs.

While we have stated that the shingles are formed from a composition of asphalt and concrete, we want it understood that the shingles can be formed from slate, clay or other similar non-flexible fire resisting material.

It is thought from the foregoing description

that the advantages and novel features of our invention will be readily apparent.

We desire it to be understood that we may make changes in the construction and in the combination and arrangement of the several parts, provided that such changes fall within the scope of the appended claim.

What we claim is:—

The combination of a plurality of layed shingles overlapping each other in one direction of the lay thereof, with joints between said shingles, cleats underlying the joints between said shingles and overlapped a considerable distance thereby at the joints, each of said cleats being formed with trough-like edges parallel with each other and at opposite sides of the joints between the shingles and opening in the direction of water flow courses upon said shingles, and hook ends on said cleats to engage with the underlying edges of the shingles at the overlap thereof, each cleat presenting at its side next to the shingles a non-protruding surface for the contact of the joint edges of said shingles adjacent each other throughout the lay of said shingles.

JOHN P. WILLOCK.
